UNITED STATES PATENT OFFICE

MAYWOOD BETHEL, OF HEXT, TEXAS

COTTON LINT TRAMPER

Application filed November 7, 1930. Serial No. 494,138.

This invention relates to a machine for tramping cotton lint, to compress it in the press boxes of a baling machine.

An object of the invention is to provide a machine of this character which will automatically feed cotton lint into the press boxes of a baling machine, in such a way as to eliminate all danger of the machine choking, to impair the operation of the machine.

10 A further object of the invention is the provision of a machine of this type constructed in such a way as to prevent the cotton lint from being fed into the press box, as the packer or tramper is moving into the 15 press box of a machine.

A still further object of the invention is to provide a machine wherein the load is not directed to the crank shaft of the machine, until the crank of the shaft has moved downwardly to a sharp angle, to the end that as the pressure under the packer or tramper increases, the ratio of the travel between the packer block and the crank increases, thereby increasing the power of the machine.

25 With the foregoing and other objects in view, which will appear as the description proceeds, the invention resides in the combination and arrangement of parts and in the 30 details of construction hereinafter described and claimed, it being understood that changes in the precise embodiment of the invention herein disclosed, may be made within the scope of what is claimed, without departing 35 from the spirit of the invention.

Referring to the drawings:

Figure 1 is a side elevational view of a cotton lint tramping machine, constructed in accordance with the invention.

40 Figure 2 is an enlarged fragmental detail view, illustrating one of the tramping bars of the tramper.

Figure 3 is a vertical sectional view through the machine, showing the tramper in its elevated position.

Figure 4 is a vertical sectional view through the machine, illustrating the tramper as moved downwardly.

50 Figure 5 is a vertical sectional view through the machine, taken from the opposite side of

the machine, and showing the tramper in its elevated position.

Figure 6 is a vertical sectional view similar to Figure 5, and illustrating the tramper as moved downwardly.

Figure 7 is a sectional view taken on line 7-7 of Figure 1.

Figure 8 is a sectional view taken on line 8-8 of Figure 7.

Figure 9 is a fragmental detail view illustrating the manner of supporting the upper ends of the tramper rods.

Figure 10 is a fragmental sectional view illustrating the lower ends of the tramper rods.

Figure 11 is a sectional view taken on line 11-11 of Figure 2.

Figure 12 is an enlarged sectional view illustrating a modified form of means for moving the sweep board to its active or inactive position.

Figure 13 is a sectional view taken on line 13-13 of Figure 9.

Referring to the drawings in detail, the machine comprises a pair of parallel channel bars 5 which are held in spaced relation with each other by means of spacing bars 6, that are bolted to the bars 5. The body portion of the machine is indicated generally by the reference character 7, and as shown is mounted on the upper edges of the angle bars 5, which act as the support for the body portion.

Extending into the body portion is the power shaft 8 which is provided with pulleys 9 and 10 respectively, the pulley 10 being loosely mounted on the shaft 8, while the pulley 9 is keyed or otherwise secured to the shaft 8 to impart rotary motion to the shaft, when the belt 11 is moved from the idle pulley 10, to the pulley 9.

The reference character 12 designates the controlling rod that has a forked end 13 engaging the belt, so that movement of the controlling rod 12, will move the belt, in a manner as described. Lever 14 connects with one end of the rod 12, so that the operator may by moving the lever 14, operate the rod 12.

Mounted on the inner end of the shaft 8, is a worm 15 that meshes with the gear 16,

that in turn is mounted on one end of the crank shaft 17, that extends through vertical channel bars 18, the shaft 17 being mounted in suitable bearings formed in the channel bars. These vertical channel bars provide supports for the channel guides 19, that are shown as bolted to the channel bars, by means of the strap 20. As clearly shown by Figure 4 of the drawings, these tubular guides 19 are formed with elongated openings 21, through which the ends of the rod 22 extend, the rod 22 being connected with the cotton packer or trumper posts 23, that connect with the trampers 24.

Connected with the crank shaft 17, are connecting rods 25 that have pivotal connection with the rod 22, so that rotary movement of the crank shaft, will result in a reciprocatory movement of the trumper posts and trampers supported thereby. Secured to the crank shaft 17, is an arm 26 that extends upwardly therefrom, the arm being provided with a roller 27 at its free end.

The reference character 28 designates a rod that has pivotal connection with one of the channel bars 18, at 29, the roller end of the rod 28 extending downwardly to a point near the arm 26. Forming a part of the rod 28, is a laterally extended flange 30, which flange lies in the path of travel of the roller 27 and arm 26, to be operated by the arm 26. Connected to the rod 28 is a chain 31 that moves over the pulley 32 that is supported in a bracket 33, secured to the inner surface of the body portion or housing.

One end of the chain 31 connects with the link 34 that in turn has pivotal connections with the arm 35 mounted on the shaft 36.

Secured to the shaft 36, are sweep arms 37 that have pivotal connection with the sweep board 38 which is designed to move through the curved lint chute 39, the inner wall of the lint chute being formed with elongated openings 40 to allow the sweep arms to move therethrough.

The spring 41 connects with the sweep board 38 and acts to normally urge the sweep board to its active position. Formed on the free edge of the sweep board 38, are spaced fingers 42 that contact with the cotton lint, to force the cotton lint through the lint chute. Thus it will be obvious that as the crank shaft 17 moves in the direction of the arrow as shown by Figure 4 of the drawings, the roller 27 at the free end of the arm 26 will contact with the flange 30 of the rod 28, moving the rod from a vertical position, to a position as shown by Figure 4, whereupon the roller 27 moves out of contact with the flange 30. When the rod 28 is moved in a manner as explained, the chain 30 is drawn from a position as shown by Figure 3 of the drawings, to the position as shown by Figure 4, resulting in the sweep board being moved throughout the length of the lint chute, car-

rying with it the lint which has been deposited in the lint chute by the doffing rolls 43.

On the opposite side of the machine, is a rocking arm 44 which is pivotally supported intermediate its ends, one end of the rocking arm lying in the path of travel of the roller 45 mounted at the free end of the arm 46, which in turn is secured to the crank shaft 17, to move therewith. This arm 44 is held in the guide 47, to insure the true operation thereof.

Secured to one end of the arm 44, is an arm 48 which has a downwardly extended end portion 49 adapted to engage under the shoulder 50 formed at the outer end of the spring arm 51.

Pivottally connected to the arm 48, is an arm 52 which in turn has pivotal connection with the arm 53 secured to the shaft 36 on which the sweep arms 37 are secured. Thus it will be seen that as the shaft 36 is rotated to move the sweep board to the lower end of the lint chute, the end 49 of the arm 48, moves against the shoulder 50, to hold the sweep arm to the limit of its downward movement, while the trumper is moving downwardly to the press box, which in the present showing is indicated by the reference character 54.

As the crank shaft continues to rotate, the roller 45 moves downwardly in the direction of the arrow as shown by Figure 6, moving the arm 44 downwardly, until it reaches the lower end of the guide 47, whereupon the roller moves over the end of the arm 44. It is of course obvious that when the arm 44 is moved in this manner, the sweep arms and sweep board connected therewith, are returned to their initial or inactive positions, at the upper end of the lint chute.

The trumper which forms an important feature of the invention, embodies a plurality of spaced members 55 which are connected by means of a substantially wide board 56, to which the lower ends of the trumper posts 23 are bolted, as by means of the bolts 57.

As clearly shown by Figure 8 of the drawings, one end of each of the spaced members 55 is formed with a cut away portion disposed intermediate the side edges thereof, the cut away portions being designed to accommodate the fingers 58, that are secured to the lower edge of the stop board 54', which fingers act to prevent material from being forced upwardly, as the trumper moves upwardly. Extending upwardly from the members 55, are slats 59, which are of lengths to cover the discharge end of the lint chute, as the trumper moves downwardly, thereby preventing material from passing from the line chute, into the press box, during the tramping operation.

Pivottally mounted on the bin 60, is an arm 61 that has a pivoted end piece 62, which end piece lies in the path of travel of the sweep

board 38, there being provided a coiled spring 63 connected with the end piece 62, to normally urge the end piece to a position as shown by figure 3 of the drawings. Thus 5 it will be seen that when the sweep arms swing upwardly to the limit of their upward movement, the sweep board will be swung forwardly, and that when the sweep arms move downwardly, the sweep board will be 10 swung outwardly to its active position.

A guard member 64 is mounted near the upper edge of the press box and acts to prevent cotton lint from being forced over the edge of the press box, as the material is being 15 fed thereinto.

In the form of the invention as illustrated by Figure 12 of the drawings, the sweep board moves over the pivoted member 65, which is provided with a coiled spring 66 20 for holding the pivoted member in its positions of adjustment, the coiled spring being connected to the pivoted member in such a way as to throw the pivoted member past dead center as the sweep board moves there- 25 over. Thus it will be seen that as the sweep board contacts with the pivoted member, the sweep board will be swung to its active or inactive position.

A stop 67 is formed on one end of the sweep 30 board, to engage the sweep arm 68 and restrict movement of the sweep board. A counterbalancing weight is indicated by the reference character 66' and as shown is connected with the cable 69 that is wound on one 35 end of the shaft 36, to the end that as the shaft is rotated to a predetermined point and released, the weight will act to counterbalance the action of the shaft.

In view of the foregoing detail description, 40 it is thought that a further detail description as to the operation of the device is unnecessary.

I claim:

45 1. In a cotton lint trumper, a press box, a trumper operating in the press box, a chute for delivering material into the press box, a sweep arm operating through the chute, a pivoted sweep board on the sweep arm, a pivoted member lying within the path of 50 travel of the sweep arm to operate the sweep board and swing the sweep board to its active or inactive position, and means for operating the trumper and sweep arm.

55 2. In a cotton lint tramping machine, a bin, a chute for receiving material from the bin, a press box into which the chute directs material, a sweep arm operating within the press box, sweep arms, a pivoted sweep board 60 mounted on the free end of the sweep arm and operating throughout the length of the chute, means in the path of travel of the sweep board for moving the sweep board to its active or inactive positions, and means for 65 operating the trumper and sweep arm.

3. In a cotton lint tramping machine, a bin, a chute for releasing material from the bin, a press box into which the chute directs material, a body portion supported above the press box, a trumper post operating 70 through the body portion and carrying a trumper operating within the press box, a crank shaft, means for transmitting movement of the crank shaft to the trumper post, a sweep arm mounted on the body portion, a 75 sweep board pivotally mounted at the free end of the sweep arm and operating through the chute for forcing material through the chute, and means for transmitting movement of the crank shaft to the sweep arm to operate the sweep arm.

In testimony that I claim the foregoing as my own, I have hereto affixed my signature.
